UNITED STATES PATENT OFFICE.

RICHARD S. M. MITCHELL, OF PORT JEFFERSON, NEW YORK.

PUMP.

Application filed July 8, 1916, Serial No. 108,128. Renewed February 28, 1922. Serial No. 539,909.

To all whom it may concern:

Be it known that I, RICHARD S. M. MITCHELL, a citizen of the United States, and a resident of Port Jefferson, Suffolk County, 5 Long Island, New York, have invented certain new and useful Improvements in Pumps, of which the following is a specification.

My invention relates to pumps of that class in which a piston travels in an annular piston chamber, and the invention aims to provide an improved pump of this class in which the piston shall during portions of its movement operate between spaced abutments as in a reciprocating pump and during portions of its movement shall operate with the annular passage interrupted or closed by an abutment only at one point, the pumped fluid being discharged through 20 a single outlet at certain periods and through a plurality of outlets at other periods, and the pump having its suction through a single inlet at certain periods and through a plurality of inlets through other periods, the 25 construction, form and arrangement of parts being such as to insure at a definite pump speed the continuous passage of fluid through one or another portion of the annular passage, resulting in a steady and relatively great discharge.

I accomplish these results by means of a piston rotatable in an annular chamber intercepted at intervals by valves or abutments having, each, a plurality of passages 35 therethrough at least one of which will present a continuity of the annular chamber when in fully opened position to permit the passage of the piston without interruption to the efficiency of the packing thereof.

40 My pump embodies the principle of the mechanical movement shown and described in my application for Letters Patent of the United States filed by me on the 17th day of June, 1915, Serial No. 34,768, of a valve 45 having a passage therethrough forming a sector of, or continuity of, an annular chamber.

The valves are operable at definite moments and in definite degrees to serve as 50 port closures, as single conduits, as double conduits, and as abutments to divide the annular chamber at one point, and at a plurality of points to form a plurality of separate cylinders, and act individually at certain periods and cooperate at other periods.

55 A further feature of my pump is that,

while I provide check valves in the present structure, under certain conditions these check valves are entirely thrown out of action by the velocity of flow through the 60 pump, and I may dispense with these check valves in certain types of pumps.

My invention is fully described in the following specification, of which the accompanying drawings form a part, in which like 65 characters refer to like parts in each of the views, and in which:

Fig. 1 is a side elevation of a pump embodying my invention;

Fig. 2 is a vertical section therethrough, 70 on the line 2—2 of Fig. 3;

Fig. 3 is a section taken on the line 3—3 of Fig. 2;

Fig. 4 is a section taken on the line 4—4 of Fig. 1;

Fig. 5 is a fragmentary view of one side 75 of a valve action control, also shown in Figs. 1, 3 and 4;

Fig. 6 is a diagrammatic view of the pump advanced from the position of the parts 80 shown in Fig. 2; and

Figs. 7, 8, and 9, are similar views showing further advanced positions.

Referring to the drawings, 10 represents a casing shown as of two members joined on 85 a central longitudinal vertical plane and provided with an annular passage or chamber 11 illustrated as circular in cross-section, with inlet ports 12 and 13, controlled by check-valves 14 and 15, respectively, and 90 with discharge ports 16 and 17 controlled by check-valves 18 and 19, respectively.

The ports 12 and 17 are controlled by a valve 20 and the ports 13 and 16 by a valve 21, said valves being identical and intercepting the annular chamber 11 at diametrically opposite points, and are shown as of the rotary type of cylindrical form the centers of which, in cross-sectional view, are slightly within the outer periphery of the 100 annular chamber 11, although this is not imperative, but the peripheries of said valves for a purpose later explained, pass inward of the inner periphery of the annular chamber 11, that is, the valves or abutments extend beyond the walls of the passage in all 105 directions transverse to the passage.

The valves or abutments 20 and 21 are each provided with a passage, 20^a and 21^a, respectively, of the exact configuration of the 110 annular chamber 11 whereby, when in the position shown at the top of Figs. 2 and 3

for the valve 21, no interruption of the surface of the chamber occurs. The valve 20 is also provided with a passage 20^a and the valve 21 with a passage 21^a the formation of which is arbitrary and which are for connecting the ports 17 and 16 with the annular chamber 11 at desired periods.

Arranged centrally of the circle described by the chamber 11 is a shaft 22 having a carrier 23 thereon for a piston 24 closely fitting the chamber 11 within which it rotates, and likewise fitting the passages 20^a and 21^a when passing through the same and in a non-leakable manner. The valves or abutments 20 and 21 are each formed with a slot opening from its passage, 20^a or 21^a, to register with the slot of the annular piston passage or chamber 11, and to receive the edge of the carrier 23, as shown in Fig. 3.

20 As shown in Figs. 3 and 4, the shaft 22 passes through glands 25 for packings 26 for the piston and carrier interposed between sleeves 27 and the central portion of the casing 10, the latter being beveled at the 25 contacting surfaces adjacent the carrier 23 to permit the packings 26 to closely approach the inner periphery of the annular chamber 11, the glands being held in place by screws 29 or the equivalent.

30 The valves 20 and 21 are provided with stems 30 and 31, respectively, passed outwardly through the casing 10 and provided, each, with a segment gear 32 enmeshed with a similar gear 33 carried by a stub-shaft 34 mounted in a bracket 35 which also supports the outer end of the respective valve stem.

40 The segment gears 33, Figs. 4 and 5, carry, each, two rollers 36 and 37 adapted to bear, alternately, on the inner surfaces of two disks 38 and 39, respectively, rigidly mounted on the shaft 22 and rotated therewith, the disk 38 having its periphery cut away at 40 and the disk 39 having its periphery cut away at 41 arranged upon opposite sides of 45 the shaft 22, with the result that when the roller 36 is riding on the inner surface of the disk 38 the roller 37 is held in the cut-away portion of the periphery of the disk 39. When the shoulder at the end of the cut-away portion of the disk 39 engages the roller 37 the latter is forced to the inner surface of the said disk, the roller 36 then entering the cut-away portion of the disk 38 50 now in position for the reception of said roller, and this transposition of the rollers to and from the inner surfaces of the respective disks rocks the respective segment gear 33 and this correspondingly rocks the respective gear 32 and the respective valve stem is 55 rocked and, with it, the valve thereof.

60 The valves are, as will be seen, rocked through a definite arc of a circle, each, and at definite moments and for definite periods, as determined by the disks 38 and 39, and 65 alternately, this valve actuator having been

found to be entirely satisfactory in actual use, but I do not limit myself thereto nor to any type of actuator as many forms thereof will suggest themselves for this particular pump or others based upon the principles 70 thereof.

In order to ensure exact continuity of the passages 20^a and 21^a with the annular chamber 11 I provide a clamp 42 on each of the valve stems 30 and 31, adjustable thereon, 75 and I provide a fixed bracket 43 having a screw 44 therein against which the respective clamp strikes when the valves 20 and 21 reach a fully opened position, the clamps forming parts of the respective segment 80 gears 32, and it will thus be seen that said gears may be set with precision so as to ensure the continuity referred to.

In Fig. 2 I have shown the valve 20 in position to serve as an abutment, the fact that 85 the periphery thereof extends inwardly of the inner periphery of the chamber 11 as hereinbefore referred to ensuring a positive seat of the valve upon the casing 10 to prevent leakage, Figs. 2 and 3, and in which position said valve presents the passage 20^a to the inlet port 12 and the passage 20^b to the discharge port 17, and the liquid pumped in at the former must pass through the chamber 11 before it can reach the latter.

95 In this figure the valve 21 is shown in fully opened position, with respect to the annular chamber 11, and serving as a closure for the ports 13 and 16, the piston 24 being shown as passing through said valve, and said piston is thus drawing in liquid through the port 12 and discharging liquid in front of it through the port 17, this position presenting the perfect rotary pump principle inasmuch as there is and can be no leakage while 100 the piston is passing through the passage 21^a.

105 By reference to Fig. 6 it will be seen that the valve 21 begins to close the chamber 11 after the piston has passed through said valve, thiereby opening the inlet port 13 to the said chamber, as well as the discharge port 16, but the valve 20 is still serving as an abutment, with the result that the liquid is being drawn in through both inlet ports 110 12 and 13 and discharged through the port 17, the discharge port 16 being still practically closed.

115 In Fig. 7 it will be seen that the valve 21 has closed the chamber 11 and the valve 20 is still in its abutment position, with the result that the chamber 11 is divided into two separate cylinders suction occurring through the port 13 and discharge through the port 17. This condition still obtains 120 with a further piston movement to the position shown in Fig. 8, but the valve 20 is now about ready to move to bring the passage 20^a into position to allow the piston to pass. In both of these positions, after a 125 130

minimum pump speed has been attained to produce a sufficient velocity of the liquid through the pump, a column of liquid will flow in through the port 12, through the 5 left side of the chamber 11, and discharge through the port 16, and this will occur at both sides of the chamber alternately when the valves are in the abutment serving positions and the piston upon the respective 10 sides of the pump, and we thus have a reciprocating pump by reason of the fact that two separate cylinders and corresponding ports are alternately brought into action, although, as stated, a rotary action also occurs 15 upon the side of the pump not occupied by the piston above a minimum pump speed because of the velocity imparted to the column of water on such side.

In Fig. 9 I have shown the valve 20 just 20 opening to permit piston passage therethrough, the liquid now being drawn in through the port 13 and part thereof discharged through the port 17, the balance of the liquid coming through the port 13 25 passing through the valve 20 and out through the port 16, the check-valves 14 preventing the flow of water outwardly through the port 12, and we thus have one inlet in action and two outlets. Above a minimum 30 pump speed the liquid passing to and out of the discharge port 16, in this position of the parts, will cause a suction which will draw liquid through the port 12 and correspondingly increase the amount discharged 35 through the port 16.

This action produces a steady discharge from the pump even at low pump speeds, and at high pump speeds the velocity of flow on the side of the pump unoccupied 40 by the piston overcomes the check-valves 14 and 15 alternately and correspondingly increases the discharge.

While I have shown an entirely satisfactory structure, based upon pumps in actual 45 use, I do not desire to limit myself to the details thereof, other than such as are set forth in the appended claims, and I reserve the right to make any desired changes which come within the spirit of the invention.

Having fully described my invention, what I claim as new, and desire to secure by Letters Patent, is:—

1. A pump, comprising a casing formed 55 with an annular passage of uniform circular cross-section and having a continuous slot opening inwardly through the wall of the passage and inlet and outlet ports leading to said passage, a rotary piston carrier extending into and by which said slot is closed, a piston in said passage connected to move with said carrier, a plurality of rotary abutments extending across said passage and controlling said ports, said abutments being 60 mounted with their axes parallel with the 65 axis of rotation of the carrier in abutment chambers intersecting said annular passage and each abutment extending beyond said passage in all directions transverse to said passage and each being formed with a passage of the same circular cross-section and the same longitudinal curvature as said annular passage and positioned to form a part of the annular passage when the abutment is turned to bring its passage into register 70 with the annular passage and having a slot opening from its passage to register with said continuous slot, and means for turning said abutments into and out of position to permit the passage of the piston and for 75 controlling said ports.

2. A pump, comprising a casing formed with an annular passage of uniform cross-section and the cross-sectional contour of which is continuously curved and having 80 a continuous slot opening inward through the wall of the passage, a rotary piston carrier extending into and by which said slot is closed, a piston in said passage connected to move with said carrier, a plurality of rotary abutments extending across said 85 passage and mounted with their axes parallel with the axis of rotation of the carrier in abutment chambers intersecting said annular passage, the casing being formed with 90 inlet and outlet ports leading to said abutment chambers, each abutment extending beyond said annular passage in all directions transverse to said passage and each being formed with a passage shaped to form a 95 part of said annular passage when the abutment is turned to bring its passage into register with the annular passage and having a slot opening from its passage to register with said continuous slot, and means for 100 turning said abutments into and out of position to permit the passage of the piston and for 105 controlling said ports.

3. A pump, comprising a casing formed with an annular passage of uniform cross-section and the cross-sectional contour of which is continuously curved and having a continuous slot opening inward through the wall of the passage, a rotary piston carrier extending into and by which said slot is 110 closed, a piston in said passage connected to move with said carrier, a plurality of rotary abutments extending across said passage and mounted with their axes parallel with the axis of rotation of the carrier in 115 abutment chambers intersecting said annular passage, the casing being formed with inlet and outlet ports leading to said abutment chambers, each abutment extending beyond said annular passage in all directions transverse to said passage and each being formed with a plurality of passages, one of which is adapted to serve as a piston passage and is shaped to form a part of said annular passage when the abutment is turned to bring 120 125 130

it into register with the annular passage, and having a slot opening from its piston passage to register with said continuous slot, and means for turning said abutments into and out of position to permit the passage of the piston and for controlling said ports.

4. A pump, comprising a casing formed with an annular passage of uniform cross-section and the cross-sectional contour of which is continuously curved and having a continuous slot opening inward through the wall of the passage, a rotary piston carrier extending into and by which said slot is closed, a piston in said passage connected to move with said carrier, a rotary abutment extending across said passage, said abutment being mounted with its axis parallel with the axis of rotation of the carrier in an abutment chamber intersecting said annular passage, the casing being formed with inlet and outlet ports leading to said abutment chamber, and said abutment extending beyond said annular passage in all directions transverse to said passage and being formed with a passage shaped to form a part of said annular passage when the abutment is turned to bring its passage into register with the annular passage and having a slot opening from its passage to register with said continuous slot, and means for turning said abutment into and out of position to permit the passage of the piston and for controlling said ports and into position to close said annular passage.

5. A pump, comprising a casing formed with an annular passage of uniform cross-section and the cross-sectional contour of which is continuously curved and having a continuous slot opening inward through the wall of the passage and inlet and outlet ports leading to said passage, a rotary piston carrier extending into and by which said slot is closed, a piston in said passage connected to move with said carrier, a plurality of ro-

45 tary abutments extending across said passage, said abutments being mounted with their axes parallel with the axis of rotation of the carrier in abutment chambers intersecting said annular passage and each abutment extending beyond said passage in all 50 directions transverse to said passage and each being formed with a passage shaped to form a part of said annular passage when the abutment is turned to bring its passage into register with the annular passage and 55 having a slot opening from its passage to register with said continuous slot, and means for turning said abutments into and out of position to permit the passage of the piston and into position to close said annular 60 passage.

6. A pump, comprising a casing having an annular chamber, an inlet and an outlet port at one side thereof, and an inlet and an outlet port at the other side thereof, a valve intercepting said chamber in the position of and controlling each set of ports, and provided with a plurality of passages therethrough, and means for actuating said valves alternately to carry each into port closure position, into position to open either respective port, into position to open both respective ports, and into position to serve an an abutment for said chamber.

7. A pump, comprising a casing having an 75 annular chamber therein and inlet and outlet ports at opposite sides thereof, a rotary valve intercepting said chamber in the position of and controlling each set of ports, a stem on each valve, a gear on each stem, a 80 supplemental gear enmeshed with each of said gears, a pair of parallel disks having recesses cut in their peripheries at opposite sides, means on said last named gears movable by said disks to rock said gears and 85 thereby said valves, and means for rotating said disks.

RICHARD S. M. MITCHELL.
